(57) **CLAIM**

The ornamental design for a hose and sensor assembly, as shown and described.

DESCRIPTION

FIG. 1 is a perspective view of a hose and sensor assembly showing my new design.

FIG. 2 is a top plan view of the hose and sensor assembly of FIG. 1.

FIG. 3 is a bottom plan view of the hose and sensor assembly of FIG. 1.

FIG. 4 is a left elevation view of the hose and sensor assembly of FIG. 1.

FIG. 5 is a right elevation view of the hose and sensor assembly of FIG. 1.

FIG. 6 is a back elevation view of the hose and sensor assembly of FIG. 1; and,

FIG. 7 is a front elevation view of the hose and sensor assembly of FIG. 1.

The broken lines illustrate portions of the hose and sensor assembly which form no part of the claimed design.
